APPARATUS FOR CRIMPING HELICAL SPRINGS IN INNERSPRING CONSTRUCTION

Joseph Gauci, Jersey City, and Aloysius J. Quinn, North Bergen, N. J., assignors to Comfort Spring Corporation, Baltimore, Md., a corporation of Maryland

Application December 28, 1949, Serial No. 135,342

14 Claims.

(Cl. 219—3)

1

The present invention relates to the assembly and tying of the coil springs of innerspring units such as used in mattresses, cushions and the like. More particularly, the invention relates to apparatus for deforming or crimping the free ends of helical tie wires, called "helicals" employed for tying a group of coil springs into the innerspring assembly. The method of crimping helicals in innerspring constructions, which may be performed by the apparatus of the present application is described and claimed in our copending application, Serial No. 135,343, filed December 28, 1949.

Machines have been devised for assembling lines of coil springs in adjacent rows with the end coils of the springs of one row overlapping corresponding end coils of those of an adjacent row, and then forming the helical and feeding it while rotating about its axis across the adjacent rows so that the helical winds or "screws" itself about the overlapped portions of the end coils. Such a machine is disclosed in Patent No. 2,470,812 granted May 24, 1949, to Joseph Gauci and Daniel Krakauer. This machine is operated cyclically in intermittent motion whereby two adjacent rows of assembled springs are advanced to a tying position in the machine where the helical is formed and screwed across the overlapped end coils and then cut off beyond the end springs of the connected rows. While this is being done, a third row of springs is assembled adjacent the second row and advanced therewith to the tying position at the start of the next cycle. This is repeated until the assembly is of required size. When it is removed from the machine and the ends of the helicals extending from the end coils of the assembly are crimped to prevent accidental displacement from the springs by unscrewing therefrom.

Various attempts have been made to perform this crimping operation automatically during the assembling operations, but so far as we are aware, no satisfactory means has heretofore been devised and the crimping is performed by hand after the spring unit has been completely assembled. The usual manner of crimping is by cutting off the overhanging ends of the helicals close to the end coils of the springs at opposite ends of the rows and then bending the ends of the wire over the end coils of the helical.

The helical is formed of wire wound into a relatively high pitch helix, and we have found that by axially collapsing or decreasing the pitch of a few end coils of the helical to bring a few adjacent coils close together, the helical is ef-

fectively prevented from unscrewing from the springs with which it is engaged. For the purpose of this application the term "crimping" shall be employed to refer to such axial closing up or collapsing the end turns or coils of the helical.

It is an object of this invention, therefore, to provide apparatus for crimping the free ends of helicals in an innerspring assembly by axially compressing the end coils of such helicals to decrease the pitch of the helix to an extent to prevent accidental removal or unscrewing of the helical from the spring unit due to rotation of the helical.

Another object of the invention is to provide apparatus of the above character in which heat and axial pressure are applied to the end coils of the helical to crimp such helical ends.

Another object of the invention is to provide apparatus of the above character which may form a part of or an attachment to an innerspring assembly machine of the type forming and applying helicals to an innerspring unit and which is operated automatically in synchronism with the assembly machine.

A still further object of the invention is to provide apparatus of the above character which incorporates a transporting and positioning mechanism for forwarding the spring unit in step by step motion and accurately positioning the helical ends in place for the crimping operation.

With the above objects and advantages in view, which will become more apparent during the course of the following description, the invention consists in the parts and combinations herein-after set forth with the understanding that various changes may be made therein, such as the size, shape and arrangement of parts or by the substitution of equivalents without departing from the spirit of the invention.

40 In order to make the invention more clearly understood, a preferred embodiment thereof has been made the subject of illustration in the accompanying drawings in which:

Figure 1 is a front elevational view partly broken away of the crimping apparatus according to this invention and forming a part of an innerspring assembly machine;

Figure 2 is a vertical cross-sectional view taken along the line 2—2 of Figure 1 and showing the immediate adjacent parts of the assembly machine;

Figure 3 is a detailed sectional view taken along the line 3—3 of Figure 1 showing a part of the spring forwarding and helical positioning mechanism;

Figure 4 is a plan view of one of the crimping units;

Figure 5 is a vertical sectional view taken along the line 5—5 of Figure 4;

Figure 6 is a fragmental sectional view, similar to Figure 5, showing the parts in position occupied when the electrodes initially contact the helicals and before the helical is crimped;

Figure 7 is a horizontal sectional view taken along the line 7—7 of Figure 6, but showing the helical after it has been crimped; and

Figure 8 is a wiring diagram showing the electrical control circuit for the crimping unit.

The crimping apparatus embraced in this invention may be operated as a separate unit to crimp the helical ends of an innerspring unit after complete assembly of the unit. Preferably, however, and in line with rapid production methods, the crimping apparatus and its associated spring transport mechanism may form a part of or be an attachment to an innerspring assembly machine of the type disclosed in Patent No. 2,470,812, referred to above, and operated in synchronism with the assembly machine to crimp the opposite ends of the helicals successively as the spring unit is being assembled by the machine. For the sake of brevity in the following description only the discharge end of the spring assembly machine, immediately adjacent the crimping mechanism, is shown in the accompanying drawings.

Referring first to Figures 1 and 2 of the drawings, there is shown the upper portion of the discharge end of an innerspring assembly machine designated generally as 1 and having a frame designated generally as 2. Journalled in the frame 2 is an intermittent motion conveyor mechanism indicated generally as 3 which holds juxtaposed coil springs in adjacent rows extending transversely across the machine in position with the top and bottom coils 4 of the springs 5 of one row overlapping the corresponding end coils 6 of the springs 7 of the adjacent row (see Figures 4 and 5). With the adjacent rows of springs thus held during a dwell period of the conveyor 3, a helical 8 is fed respectively across the line of overlap of the top and bottom coils of the adjacent rows of springs. The leading end of the helical is fed a predetermined distance beyond the last coils of the rows to leave a free end extension 9. The following end of the helical is cut off an equal distance from the opposite end coils of the connected rows to provide a similar free end extension. After each succeeding pair of helicals are applied, the spring unit is advanced the distance between spring rows of the unit, the spring being discharged from the conveyor 3 and the unit discharging from the discharge end of the machine.

At the discharge end of the machine there is provided a series of vertically aligned, horizontal tracks 10 and 11 constituting a guide way 12 through which the spring unit moves as it is discharged from the machine. The tracks 10 and 11 are respectively secured at their opposite ends to cross rails 13 joined to the opposite sides of the frame 2 and extending transversely across the discharge end of the machine. Preferably the tracks are arranged so that one pair of tracks 10 and 11 respectively engage the top and bottom coils of each spring to hold them under slight compression with the top and bottom helical extensions 9 parallel and spaced a fixed distance apart.

Mounted to reciprocate between the rails of the guide way 12 is a spring transporting mechanism indicated generally as 14 for forwarding the spring unit step by step and positioning the helical extensions in position for crimping.

Constituting the transport mechanism 14 is a slide block 15 which is mounted for longitudinal movement (fore and aft of the machine) between one of the tracks 11 adjacent the left-hand side of the machine (as viewed in Figure 1) and a parallel rail 16 which is secured between the lower cross rails 13 and below the said track 11. A slide block 17, similar to the slide block 15, is mounted for movement between one of the lower tracks 11a, adjacent the right-hand side of the machine, and a parallel rail 16a similar to the rail 16 and similarly secured to the cross rails 13. Extending between the slide blocks 15 and 17 is a cross rod 18 which extends beyond the slide blocks and is rigidly secured thereto.

Secured to the left-hand extension of the cross rod 18, beyond the slide block 15 (see Figure 1), is a spring forwarding member designated generally as 19, and secured to the right-hand extension of the cross rod 18, beyond the slide block 17, is a similar spring forwarding member designated generally as 20. The members 19 and 20 are essentially alike except that one is made right-hand and the other left-hand, and the same reference characters are applied to like parts on both members.

The spring forwarding members 19 and 20 each comprise a lower block 21 having a transverse hole therein which receives the cross rod 18 and in which this rod is secured. An upper block 22 is positioned vertically above the block 21 and is joined thereto by vertical plate 23. The upper block 22 of each of the members 19 and 20 is provided with a transverse hole, one axially aligned with the other, and an upper cross rod 24 extends between the members 19 and 20 and is secured in these holes in the blocks 22.

Secured to the inner end face of each of the lower blocks 21, for fore and aft pivotal movement, is an upstanding hook member 25. ("Forward" as used herein is the direction corresponding to the movement of the spring unit toward the discharge end of the machine, or to the left as viewed in Figure 2.) The forward face of each hook member 25 at the upper or free end thereof, is formed with a slight hook 26 while the upper rear face is formed with a downward and rearward bevel 27. Each hook member has a downwardly facing shoulder 28 on its forward edge and between this shoulder and a shelf 28a on the block 21 is positioned a compression spring 29 which urges the hook member in a rearward direction about its pivotal axis. This rearward pivotal movement is limited, however, to a substantially vertical position of the hook member by a pin 30 on the block 21 which engages the rear edge of the hook member. A similar but downwardly extending hook member 31 is similarly mounted on each of the upper blocks 22 in vertical alignment with the corresponding hook member 25.

The blocks 21 and 22 of the respective spring forwarding members 19 and 20 are vertically aligned and lie substantially in the paths of movement of the axes of the end springs of the spring unit. The hook ends 26 of hook members are horizontally aligned respectively with the top and bottom helicals of the spring unit moving between the tracks 10 and 11. The connector

plates 23 of the spring forwarding members are sufficiently offset from the hook members to clear the end springs of the unit.

A connecting rod 32 has a connection at one end thereof with the lower cross rod 18 adjacent the block 15 while a second connecting rod 33 has a similar connection with the rod 18 adjacent the block 17. The opposite ends of the rods 32 and 33 are respectively connected to the free ends of a pair of crank arms 34 and 35. The cranks 34 and 35 are respectively secured to the inner ends of a pair of axially aligned rotary drive shafts 36 and 37 which extend inwardly respectively from opposite sides of the machine and are journalled respectively in bearings 38 and 39 carried by the frame of the machine. The throw of the cranks 34 and 35 is such as to move the spring forwarding members 19 and 20 from a forward dwell position (shown in full lines in Figure 2) to a position rearwardly thereof a distance somewhat in excess of the horizontal spacing between adjacent helicals in the spring unit, and then back to the forward dwell position. The hook ends 26 of the hook members 25 and 31 are aligned vertically with the top and bottom helicals of the spring unit as stated above, and it will be seen that as the hook members are moved rearwardly they will, upon engagement with a pair of helicals, pivot forwardly to pass the helicals and then, upon forward movement, will engage the helicals and move the spring unit forwardly until the engaged helicals reach the forward dwell position.

Preferably the hook members engage the helical about the center of the end springs of the rows engaged thereby. Spring units are made, however, in various widths (6, 7, 9 or 10 springs wide) counted from the right-hand side of the input end of the machine or left-hand side looking from the discharge end as in Figure 1. The forwarding member 19 on the left-hand side of the machine, therefore, has a fixed transverse position aligned with the number one line of springs of the unit. The associated shaft 36, bearings 38, crank 34 and rod 32 also have fixed transverse positions on the machine. The right-hand forwarding member 20, on the other hand, may be slid along the rods 18 and 24 so that the hook members will vertically align with the center of the opposite end springs of whatever width unit is being assembled.

The shafts 36 and 37 have operative connections through suitable power transmission mechanism (not shown) to rotate them in unison through one complete revolution for each step of movement of the conveyor 3 and in synchronism with the conveyor movement.

Secured to a cross angle rail 40, forming a part of the rear framework of the assembly machine is an upstanding bracket 41 having a fixed position at the left-hand side of the machine. Also secured to the rail 40 is a similar upstanding bracket 42. Each of these brackets carries a helical crimping unit designated respectively and generally as 43 and 44. The bracket 42 is adjustable along the rail toward and away from the bracket 41 to position the crimping unit carried thereby according to the width of the unit being assembled, as will be more clearly understood hereinafter. The crimping units 43 and 44 are essentially alike except that they are oppositely operated, and only the right-hand unit will be described in detail, the same reference characters designating like parts in both units.

As best seen in Figures 4 and 5, the crimping

unit comprises a rectangular plate 45 which is secured to the upper end of bracket 42. Secured to the face of the plate 45, away from the center of the machine, is the winding 46 of a solenoid 47 which is provided with an axially movable armature or plunger 48. The solenoid plunger 48 extends from the winding through an opening 49 in the plate 45 toward the center of the machine and has secured thereto a vertically elongated head 50. The head 50 carries a pair of sleeves 51 and 52 which project toward the center of the machine and are aligned axially respectively with the top and bottom helical extensions 9 when the helicals are positioned in the forward or dwell position of the spring forwarding members 19 and 20. The head 50 is guided for horizontal movement by a pair of pins 53 which are secured to the plate 45 and pass through apertures 54 in the head 50. Pins 53 have enlargements at their free ends to limit the inward or extended movement of the head.

Urging the plunger 48 and its head 50 to a retracted position, where the sleeves 51 and 52 will clear the path of movement of the helical extensions, are compression springs 55 which are positioned between a bar 56 secured to the outer end of the plunger 48 and brackets 57 secured to the solenoid.

Secured in the head 50 are a pair of pins 58, 30 perpendicularly to the head and extending oppositely from the sleeves 50 and 51 and each having a head on its free end. Mounted for sliding movement on the pins 58 is a bar 59 which is 35 yieldingly urged toward the head 50 by a pair of relatively light compression springs 60 which are positioned respectively around the pins 58 between the bar 59 and the heads of the pins. It is to be noted that the springs 60 are lighter, or exert less force than retracting springs 55, and it 40 might also be noted here that the force exerted by the springs 60 is not sufficient to overcome the stresses in the helical in its normal cold state.

Rigidly secured to the bar 59 and insulated therefrom are a pair of electrodes 61 and 62 which extend respectively with a sliding fit in insulating bushings 63 and 64 respectively fitting concentrically within and forming parts of the sleeves 51 and 52. It will be noted that the lengths of the electrodes are such that in normal expanded condition of the spring 60, where the bar 59 engages the head 50, the tips of the electrodes lie closely adjacent the outer ends of the bushings 63 and 64 which, it will be seen, are outwardly bevelled—the front faces of the electrodes lying approximately at the rear end of the bevels. The electrodes 61 and 62 are fitted respectively with connector strips 65 and 66 for connecting the electrodes in a circuit (to be described) with a source of current.

Describing now the control circuit for the solenoids and electrodes, reference is made to Figure 8 where it will be seen that one side 67 of an electric power line has a connection through a lead 68, and the contacts of a normally open switch 69 (to be further described) with the winding 70 of a two-contact, normally open relay 71. From the winding 70 a return is made through a lead 72 to the return line 73 of the power supply. A connection is made from the power line 67 through a lead 74 and one set of the normally open contacts 75 of the relay 71 with one end of the winding 46 of both solenoids 47, the opposite ends of which are connected through a lead 76 to the return power line 73. The power line 75 has a connection through a lead 77, the other

normally open contacts 78 of the relay 71, and a time interval relay 79 with the winding 80 of a single contact, normally open relay 81. The winding 80 has a return lead to the power line 73 through a lead 82. A lead 83 connects the power line 67 through the normally open contacts 84 of the relay 81 with the primary 85 of a pair of transformers 86, the return leads from which are made to the power line 73 through a lead 87. The opposite ends of the secondary windings 88 of the transformers 86 are connected through leads 89 and 90 respectively with the electrodes 61 and 62, the electrodes of one crimping unit being connected to one of the transformers 86 and the electrodes of the other unit being connected to the secondary of the other transformer.

The crimping unit is operated when the helicals connecting a pair of adjacent rows of springs are positioned in crimping position between electrodes 61 and 62, i. e., in the forward dwell position of the spring transport mechanism. To this end the switch 69 may be placed in a position on the machine to operate, or be closed at the start of a dwell period of the machine. A convenient location for the switch is at the forward location of one of the slide blocks of the transport mechanism as seen in Figure 2. This switch may be of conventional quick acting design such as a normally open "micro" switch and may be mounted on one of the lower rails 16 carrying the bottom slide block 15 and be closed thereby as the block reaches its forward position by means of a rocker arm 91, one end of which is contacted by the block 15 and the opposite end of which depresses the plunger of the switch to close the switch contact.

In operation a spring unit is assembled in the machine as briefly described above and as more fully described in Patent No. 2,470,812. It will be recalled that the helical is applied in the machine during a dwell period of the holding conveyor 3, which is also the dwell period of the transporting mechanism. As the successive rows of springs are connected by the helicals, they are advanced through the discharge end of the machine and into the guide way 12 between the track 10 and 11 which horizontally align the end coils of the springs and the top and bottom helicals engaged thereby.

When the first connected rows of the spring unit has reached the rear location of the transport mechanism stroke and as the conveyor 3 is operating to move the next rows of springs to be connected into helical applying position in the machine, the spring forwarding hook members move rearwardly, fall behind the helicals of the first connected rows and then move forwardly to advance these rows through the guide way 12 and position the helical ends 9 in axial alignment with the electrodes 61 and 62. While the next helical is being formed and applied to the spring rows in applying position in the machine, the conveyor 3 and the spring transport mechanism 14 remain stationary in their respective dwell position for a time sufficient to form and apply the helicals.

When the slide blocks 15 and 17 move up to their forward position, the block 15 engages the rocker arm 91 and closes the switch 69 which completes the circuit from the power line 67—73 to the winding 70 of the relay 71, energizing this relay and causing it to drop in and close its normally open contacts. When the relay 71 drops in, circuit is completed to the windings 46 of the solenoids 47 and also to the winding 80 of the relay 81 through the normally closed time interval relay 79, energizing both solenoids 47 and caus-

ing the relay 81 to drop in and close its normally open contacts 84. Closing of the relay contacts completes the circuit from the power supply to the primaries of both of the transformers 86.

As the solenoids 47 become energized, their plungers will be advanced, advancing the heads 50 and the sleeves 51 and 52 toward the ends of the helical extensions 9. Due to the resilient connection of the springs 60 between the head 50 and the electrode supporting bar 59, the electrodes are also advanced until their tips contact the extremities of the helical extensions. Here the blocking resistance offered by the relatively stiff helicals overcomes this force of the springs 60 and electrode movement stops. The head 50 continues to advance, however, to the full extent of solenoid plunger movement and the sleeves 51 and 52 advance, relatively to the electrodes and telescope over the ends of the helical extensions as shown in Figure 6.

When the electrodes 61 and 62 respectively contact the ends of the top and bottom helical extensions, a circuit is completed through the secondary of the transformer 86 and current flows from one electrode, through one helical extension, thence through the springs engaged by the helicals and through the other helical extension to the other electrode. Due to the fact that the wire composing the helical is of relatively small diameter, compared to the mass of the springs, the current takes the above path and because the small diameter wire of the helicals has relatively high electrical resistance, the extensions become rapidly heated, and relatively soft by removal of internal stresses. When sufficiently annealed or softened whereby the helical extensions offer less force than the springs 60, the force of these springs advance the electrodes toward the helicals and axially compress or collapse the heated convolutions of the helical extensions compressing them into close juxtaposition as shown in Figure 7. In order to prevent over-heating and burning the wire of the helical extensions, the time interval relay 79 is designed or adjusted to open after the helical coils have been softened just sufficiently to be compressed by the springs 60. Opening of the relay 79 breaks the circuit to the relay 81, causing this relay to drop out and open the power circuit to the transformer 86.

At the start of the next cycle of the machine, and as the forwarding mechanism starts its retracting movement, the block 15 releases from the rocker arm 91 allowing the switch 69 to open and break the energizing circuit to the relay 71, allowing this relay to drop out and break the energizing circuit to the solenoids 47. As the solenoids become de-energized, the springs 55 retract the plungers and heads 50 with their sleeves 51 and 52 moving these out of the paths of the springs and permitting the spring unit to again be advanced to bring the next pair of helicals into crimping position.

From the foregoing it will be seen that the invention provides a relatively simple, rapid apparatus for crimping helical ends and moreover one which can be fully automatic in operation as a part of or attachment to an innerspring assembly machine and accurately timed for synchronous operation therewith.

We claim:

1. Apparatus for crimping a helical of an innerspring unit wherein the helical has a free end extension from the springs engaged thereby comprising means for exerting axial pressure on the

extremity of said free end of the helical extension, and means for passing an electric current through said pressure exerting means, said free end extension, and through the springs engaged thereby, to heat the free end extension to an annealing temperature whereby the axial pressure compresses the helical.

2. Apparatus for crimping a helical of an innerspring unit wherein the helical has a free end extension from the springs engaged thereby comprising means for passing an electric current through said free end extremity to heat the same to an annealing temperature, said current passing means including a movable electrode in axial alignment with the extension and engaging the free extremity thereof, and resilient means exerting a yielding pressure on the electrode axially of the extension and toward the same to axially collapse the coils of the helical extension heated by said current.

3. Apparatus for crimping a helical of an innerspring unit wherein the helical has a free end extension from the springs engaged thereby comprising means for passing an electric current through said free end extremity to heat the same to an annealing temperature, a guide sleeve adapted to axially receive said extension, said current passing means including an electrode mounted for axial movement in said sleeve to engage the free extremity of said helical extension received in the sleeve, and resilient means exerting a yielding pressure on the electrode and urging the same axially toward the helical extension to axially collapse the coils thereof heated by said current.

4. Apparatus for crimping helicals of an inner-spring unit, wherein a helical engages top and bottom coils respectively of springs in adjacent rows thereof and the helicals have free end extensions from the end springs of said rows, comprising a pair of electrodes, support means mounting the electrodes respectively for axial movement along the axes of said helical extensions respectively at the top and bottom coils of said springs, resilient means for urging the electrodes axially into pressed engagement with the free extremities of the helical extensions, and means for passing an electric current from one to the other of said electrodes through said helical extensions and to heat the same to annealing temperature whereby said extensions become axially collapsed under the pressure of the electrodes.

5. Apparatus according to claim 4 including a pair of non-conductive sleeves carried by the support means and in which said electrodes respectively are mounted for axial movement, said sleeves serving respectively to receive the helical extensions and axially align the same with the electrodes.

6. Apparatus according to claim 5 including a support for the spring unit having spaced parallel rails engaging the end coils of said springs and holding the helical extension axes in planes which include respectively the axes of said sleeves, and means for moving the springs between said rails into axial alignment with said sleeves.

7. Apparatus for crimping helicals of an inner-spring unit, wherein a helical engages top and bottom coils respectively of springs in adjacent rows thereof and the helicals have free end extensions from the end springs of said rows, means for supporting at least the end coils of a pair of adjacent spring rows with the spring extension in fixed parallel relationship and spaced a pre-

determined distance apart, a pair of non-conductive cylindrical sleeves having inside diameters to closely receive respectively said extensions, a movable support for the sleeves positioning the same in axial alignment with said extensions, said support having a normal retracted position holding the sleeves in spaced axial relation to the free extremities of the extensions, an electrode mounted for concentric axial movement within each sleeve, compression means urging the electrodes to forward positions adjacent the ends of the sleeves facing the extensions, means for advancing the support to telescope said sleeves over the helical extensions retracting the electrodes into the sleeves against the force of said compression means, and means for passing an electric current from one to the other of said electrodes through said helical extensions to heat the same to annealing temperature whereby the force of said compression means acting on the electrodes will axially collapse the annealed coils of the helical extensions.

8. Apparatus according to claim 7 including spring means urging said support to the retracted position thereof, solenoid means for advancing the support, circuit means for simultaneously connecting said solenoid and said electrodes with a source of current, and means for breaking said circuit.

9. Apparatus according to claim 8 in which said circuit breaking means includes a time interval relay in series with said electrodes to break the circuit to the electrodes after a time interval calculated to heat the extensions sufficient to permit axial collapse thereof under the force of said compression means.

10. In a machine for assembling innerspring units of the type in which adjacent rows of coil springs are connected by helicals encircling adjacent portions of corresponding top and bottom coils respectively of the springs of said adjacent rows, the said helicals having free end extensions from opposite ends of said rows, the machine including intermittently operated conveyor means for successively positioning adjacent rows of springs at a station in the machine to receive said helicals during dwell periods of the conveyor means and subsequently advancing said adjacent rows beyond a discharge end of the machine, the improvement comprising a pair of electrodes positioned adjacent the discharge end of the machine, respectively and in normally spaced axial relation to the opposite extremities of said extensions, one electrode of each pair being axially aligned respectively with the top and bottom extensions in a dwell position of the conveyor, support means for each pair of electrodes including resilient compression means backing up the electrodes, power means synchronized with said conveyor means to move the support means toward the spring unit and move the electrodes axially into yielding engagement with the extremities of the extensions adjacent thereto during said dwell periods, and means for passing an electric current from one to the other electrode of each pair through the helical extensions while engaged thereby to heat said extension to annealing temperature whereby said compression means acting on the electrodes will axially collapse the coils of the extensions heated by said current.

11. Apparatus according to claim 10 including guiding support means for the spring unit receiving the same at the discharge end of the machine and guiding the helical extensions in planes respectively including the electrodes, and

transporting mechanism operating in synchronism with said conveying means engaging the helicals and positioning the extensions thereof in axial alignment respectively with the electrodes during said dwell period.

12. Apparatus according to claim 11 in which the power means for moving the electrodes comprises solenoid means, circuit means for connecting this solenoid means with a source of energizing current and switch means in the circuit means operative by movement of the transport means into helical aligning position to close the circuit means.

13. Apparatus according to claim 12 including a circuit also closed by said switch means for connecting the electrodes to the source of current, said electrode circuit including a time interval relay in series with the electrodes to break the circuit thereto after a predetermined heating interval of time.

14. In a machine for assembling innerspring units of the type in which adjacent rows of coil springs are connected by helicals encircling adjacent portions of corresponding top and bottom coils respectively of the springs of said adjacent rows, the said helicals having free end extensions from opposite ends of said rows, the machine including intermittently operated conveyor means for successively positioning adjacent rows of springs at a station in the machine to receive said helicals during dwell periods of the conveyor means and subsequently advancing said adjacent rows beyond a discharge end of the machine, the improvement comprising a pair of electrodes positioned adjacent each side of the discharge end of the machine, movable supports for said electrodes for positioning them in normally spaced axial relation to the opposite extremities of said extensions, a non-conductive sleeve surrounding each electrode and in which the electrodes are axially movable, said sleeves being carried by the electrode support and respectively receiving the helical extensions upon movement of the support toward the spring unit,

one electrode of each pair being axially aligned respectively with the top and bottom extensions in a dwell position of the conveyor, said electrode supports including resilient compression means 5 backing up the electrodes, power means synchronized with said conveyor means to move the support means toward the spring unit and move the electrodes axially into yielding engagement with the extremities of the extensions adjacent thereto during said dwell periods, guiding support means for the spring unit receiving the same at the discharge end of the machine and guiding the helical extensions in planes respectively including the electrodes, transporting mechanism operating in synchronism with said conveying means engaging the helicals and positioning the extensions thereof in axial alignment respectively with the electrodes during said dwell period, and means for passing an electric current 10 from one to the other electrode of each pair 15 through the helical extensions while engaged thereby to heat said extension to annealing temperature whereby said compression means acting on the electrodes will axially collapse the coils 20 of the extensions heated by said current.

JOSEPH GAUCI.
